LATCH TRIPPING MECHANISM

Robert A. Shields, Bloomsburg, Pa., assignor to ACF Industries, Incorporated, a corporation of New Jersey

Application July 12, 1951, Serial No. 236,425

9 Claims. (Cl. 214—58)

This invention relates to latch tripping mechanisms in general, and in particular to latch tripping mechanisms for use with automatically operated drop bottom door mine cars. Drop bottom mine cars have in the past been tripped by trackside mechanism exacting an upward pressure either on an arm projecting to the side of the car or upon a mechanism mounted beneath the car. With either of these mechanisms it is necessary that the locomotive and other types of cars ride over the tripping mechanism or the tripping mechanism must be moved to one side. In cases where the locomotive rides over the mechanism excessive wear takes place due to the necessary heavy upward pressures which is increased due to the collapsed position of the tripper. It is an object therefore of the present invention to provide a tripping mechanism in which the upward pressure decreases between the upright and collapsed position.

A further object of the invention is the provision of a tripping mechanism which is resiliently held in a raised position and trips the car latches by downward pressure.

A still further object of the invention is the provision of a latch tripping mechanism having the parts so arranged that the erecting leverage decreases at a faster rate than the spring tension increases during collapse of the tripping mechanism.

A yet further object of the invention is the provision of a latch tripping mechanism which may be used to trip various types of latches.

These and other objects of the invention will be apparent to persons skilled in the art from a study of the following description and accompanying drawings, in which

Fig. 1 is a side elevation of the improved tripping mechanism;

Fig. 2 is a plan view of the mechanism;

Fig. 3 is an end view of the mechanism showing the relation to a car; and

Fig. 4 is an elevational view showing the relation of the tripping mechanism to the cars and dumping pit.

Referring now to the drawings in detail it will be seen that the tripping mechanism indicated generally at A is adapted to be located alongside the track and at the approach side of the bin B. The cars C travelling along the track are equipped with drop bottom doors D and a latch mechanism connected to a tripping arm E. As clearly shown in Fig. 4, the tripping mechanism is permanently mounted on the trestle or permanent structure with the arms in position to engage the tripping arm E, thereby unlatching the doors and permitting them to open when they reach the dumping bin B.

The tripping mechanism, as clearly shown, is formed with a base portion having a base plate 2 provided with holes 4 by means of which the base may be bolted or otherwise fastened to the trackside structure. Spaced plates 6 project upwardly from the ends of base plate 2 and are suitably gusseted to the base, as at 8. They are also stiffened by a crosstie 10, welded or otherwise secured to plate 6 above pivot pins 12. The pivot pins

2

12 extend through the upstanding plate 6, and are longitudinally movable in slots 14 formed in the plate 6. Inwardly of the pivot pins and between plate 6 a pair of lugs 16 are welded, and at least one of these is threaded to receive an adjusting screw 18. The remote ends of the adjusting screws are adapted to bear upon rollers 20 carried on pivot pins 12, and adapted to roll along base plate 2, thereby relieving any wear on the pivot pins.

10 A pair of lever arms 22 and 24 of generally inverted channel cross-section are provided, and have the lower ends of their flanges pierced to engage the pivot pins 12 and have a portion of the web cut away to clear rollers 20. The upper ends of the flanges of arm 22 are pierced to receive a pivot pin 26 extending through the flanges and also through plates 28 welded internally of the flanges of lever arm 24, thereby in effect forming continuations of the flanges. A filler plate 30 is mounted on the pivot pins 26 intermediate the plates 28, thereby forming a bearing point to engage the intermediate portion of a tension spring 32. The ends of the tension spring are connected by pins or bolts 34 to the flanges of arms 22 and 24. In order to prevent distortion, the flanges are connected, as at 36, by plates welded to the flanges and preventing any spreading or squeezing tendency that might be imparted by bolts 34. In order to trip the car latches, a tripping projection 40 is welded or otherwise secured to the lever arm 22 adjacent its upper end, and this projection is adapted to engage over the outwardly projecting latch control arm E.

As shown in Fig. 1, the arms 22 and 24 make an angle of approximately 22½ degrees with respect to the base or with respect to the line of pull of spring 32. When the device is collapsed beneath a locomotive end into the dotted line position, these angles are approximately 6 degrees. By arranging the lever arms and spring connections, as shown, it is obvious that the tension in spring 32 will increase during collapse of the tripper as the cosine of the angle. It is also obvious that during collapse the leverage through which the spring can act will decrease as the sine of the angle. It is well known that as an angle approaches zero, the sine of the angle also approaches zero at a much faster rate than the cosine approaches unity. With parts connected as shown, the erecting pressure will decrease and be materially less in the collapsed position than in the upper or raised position. With the parts as shown, this decrease is approximately one-third, thereby giving an extremely soft action, preventing damage to the underparts of the locomotive or other structures passing over the tripping device.

From the preceding description it is obvious that by adjusting the stop screws 18 the height of tripping projection 40 may be nicely adjusted and held to a definite relation with respect to the base. When a locomotive moves toward the dumping bin, it will strike arm 24, thereby forcing pivot pin 26 downwardly and causing the pin 12 of arm 22 to move outwardly in its slot 14. As soon as this pin strikes the end of its slot, then the pin 12 of arm 24 will move outwardly in its slot, permitting the mechanism to assume the dotted line position. In the movement from the raised to the lowered position, the spring 32 will have its tension increased slightly, but at a much less rate than the leverage arm has been decreased. As soon as the locomotive has passed over the tripper, the spring will pull the arms to their raised or full line position with the rollers 20 bearing against adjusting screws 18. As soon as the latch tripping arm E comes in contact with projection 40, it will be urged downwardly, since the projection is held in its raised position by the spring and by the engagement of rollers 20 with adjusting screws 18.

In certain cases it may be desirable to pass cars without tripping, and this may be accomplished either by pulling the tripper down by mechanism (not shown), or it may be locked in a down position by inserting a pin 42 through holes in one pair of side plates 6 and above the web of an arm such as 22. In certain instances where cars of the type shown in Fig. 3 operate in train with the conventional cars having arms extending to the side of the car and tripped by upward pressure, then the pin 42 may be again inserted through the holes in plate 6 and through aligned holes in the depending flanges of arm 22. Thus this same pin may lock the tripping device in either the down or the raised position. In certain cases it will, of course, be undesirable to lock the device in the raised position, but the conventional cars may be tripped by increasing the tension of spring 32 by adjusting its connection with the arms, thereby giving sufficient tension to trip the conventional latch arm, which in this case will ride up along the arm 24.

While the invention has been described more or less in detail with specific reference to the drawings, it will be obvious that various modifications and rearrangements of parts may be made without departing from the scope of the claims defining my invention.

What is claimed is:

1. In a car door latch tripping device, a base member adapted to be mounted adjacent the trackway, a pair of levers pivotally mounted on the base member for upward and downward swinging movement, said pivotal mount including a sliding connection between the levers and base, means carried by said levers to yieldingly hold said levers in a raised position, means to limit the upward swinging and sliding movement of said levers, and means connected to one of said levers and adapted to engage a car carried latch operator part and exert downward pressure thereon to move the operator part downwardly during movement of the car past said tripping device.

2. The structure of claim 1 characterized in that said last-named means comprises a projection extending laterally from one side of said one lever and sloping downwardly longitudinally of the trackway and in the direction of car travel during tripping.

3. The structure of claim 1 characterized in that said second-named means comprises stop members adjustably carried by said base and engaging the levers whereby the uppermost and innermost position of said levers may be controlled.

4. In a car door latch tripping device, a base member adapted to be mounted adjacent the trackway, a pair of levers pivoted together at their upper ends and diverging downwardly, each lever at its lower end having a pivotal and translational mounting on said base member for upward and downward swinging and sliding movement, resilient means connected only to and acting on said levers to normally hold the same in upward position, means connected to said base and controlling the translational movement of the lower ends of the levers, and means connected to one of said levers and adapted to engage a car carried latch operator part and exert downward pressure thereon during movement of the car past the tripping device.

5. In a car door latch tripping device, a base member adapted to be mounted adjacent the trackway, a pair of levers pivoted together at their upper ends and diverging downwardly to spaced apart pivotal and translational mountings at their lower ends on said base member for upward and downward swing and sliding movement, said mountings limiting the upward movement of said levers, resilient means carried by and acting on said levers to normally hold the same in upward position, and means

connected to one of said levers and sloping downwardly longitudinally of the trackway in the direction of car travel during tripping and adapted to engage a car carried latch operator part and exert downward pressure thereon.

6. In a car door latch tripping device, a base member adapted to be mounted adjacent a trackway and including upwardly extending side plates, horizontal slots formed in said side plates, a pair of levers having their lower ends pivotally and slidably mounted in said slots and their upper ends pivoted together to form an inverted V, resilient means carried by said levers and normally holding the upper ends of said levers in upwardly spaced relationship to said base, and means connected to one of said levers and adapted when the levers are in raised position to engage a car carried latch operator part and exert downward pressure thereon to move the part downwardly during movement of the car past the tripping device.

7. In a car door latch tripping device, a base member adapted to be mounted adjacent a trackway and including upwardly extending side plates, horizontal slots formed in said side plates, a pair of levers having their lower ends pivotally and slidably mounted in said slots and their upper ends pivoted together, resilient means connected to said levers and together therewith forming an A frame, and a projection connected to one of said levers adjacent the apex of the A and adapted to engage a car carried latch operator part and exert downward pressure thereon during movement of the car past the tripping device.

8. In a car door latch tripping device, a base member adapted to be mounted adjacent the trackway, tripping means adapted to engage a car carried latch operator part and exert downward pressure thereon during movement of the car past the tripping device, and means connected to said tripping means and to said base and normally holding said tripping means in a raised position to contact the latch operator part but movable to a lowered position incapable of contacting the latch operator part, said means including resilient means connected to the tripping means and having the leverage varied during movement of the tripping means so as to exert greater raising effort on the tripping means when in raised position than in lowered position.

9. In a car door latch tripping device movable between a raised and lowered position, a base member adapted to be mounted adjacent a trackway and including upwardly extending side plates, horizontal slots formed in said side plates, a pair of levers having their lower ends pivotally and slidably mounted in said slots and their upper ends pivoted together, resilient means connected to said levers intermediate their common pivotal connection and their lower ends, said common pivotal connection moving downwardly toward said resilient means during downward swinging movement of said levers whereby the effective leverage is varied so that the resilient means will exert greater raising effort on the tripping means when in raised position than when in lowered position.
